(57) **CLAIM**

The ornamental design for a tablet container for dispensing tablets, as shown and described.

DESCRIPTION

FIG. 1 is a top, front and right side perspective view of a tablet container for dispensing tablets showing our new design

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a vertical cross-sectional view thereof taken along the line 8—8 in FIG. 2;

FIG. 9 is a horizontal cross-sectional view thereof taken along the line 9—9 in FIG. 2.

FIG. 10 is a bottom, front, and right side perspective view thereof; and,

FIG. 11 is a top, front, and right side perspective view thereof, with the lid portion omitted.

The broken-lines in the views are understood to illustrate portions of the article in which the claimed design is embodied, but which form no part of the claimed design. Where a broken-line abuts a claimed surface shown in unbroken lines and provided with surface shading, that broken-line is understood to represent an unclaimed boundary between claimed and unclaimed surfaces.
